PROTECTOR MOTION FOR LOOMS

James Chapman, Atlanta, and Benjamin W. Brown, Hapeville, Ga.

Application July 10, 1933, Serial No. 679,764

9 Claims. (Cl. 139—345)

Our invention relates to loom protection mechanism and it is an object of the same to reduce to a minimum the movement of such parts of known types of looms, as the protector rod and parts connected therewith.

Another object of the invention is to provide a simple, cheap, effective mechanism of the character described, which shall operate with a relatively little use of power, and the use of which 10 results in a saving in general wear and tear of the loom, and particularly in such parts as shuttles, belts, picker-sticks, picker lug straps, lug-sticks, pick-balls, hangers, etc.

In looms such as that shown in the accompanying drawing it has heretofore been customary to include a dagger which normally is in position to knock off the shipper handle in case the shuttle does not enter the box. A properly boxed shuttle reacts on the parts in such a way 20 as to move the dagger into an idle position, i. e., out of position of protection, thus allowing the operation of the loom to continue. Assuming now that the loom runs 172 picks to the minute, this means that the dagger and coacting parts 25 have to oscillate 103,200 times in ten hours, the dagger and coacting parts being of course operated at each pick. According to our invention, the dagger is normally out of position of protection and remains stationary during the normal 30 operation of the loom, i. e., so long as the shuttle enters either box, but should the shuttle fail to be properly boxed, then the dagger, according to our invention, will be moved positively and certainly into the position of protection, so as to 35 knock the shipper handle and stop the loom. Such a movement will very rarely be necessary, certainly not more than once a day and probably not more than once a week, instead of the continual movements of the dagger and dagger rod in previously known devices.

Referring to the drawing, which is made a part hereof, and in which similar parts are indicated by similar reference characters:

Fig. 1 is a transverse section of so much of a 45 conventional loom as is necessary to illustrate the operation of our invention;

Fig. 2 is a section on line 2—2 of Fig. 1;

Fig. 3 is a perspective of parts shown in Figs. 1 and 2.

50 In the drawing certain conventional parts of a loom are shown, including a portion 10 of the fixed frame of the loom, the frog 11, the lay 12, shuttle boxes 13 and 14, shuttle binders 15 and 16, picker-sticks 17 and 18 and binder springs 19 and 20. A protector rod 21 is journalled in bear-

ings 22 carried by the lay, this rod being provided at one end with a dagger 23. The dagger, as usual, coacts with the frog 11 to stop the loom when the dagger is operatively positioned, but is normally held in the position shown in Fig. 2 by means of two coil springs 25 instead of the usual one spring, which springs turn the protector rod opposite to the usual coil spring on said rod. The protector rod is also provided at the right hand end with a dagger 26.

Adjacent the left hand end of the lay there is journaled a shaft 27 in substantially vertical position, the mounting of said shaft being such that the shaft can oscillate and can also slide axially. At its upper end the shaft is provided with a rock arm 28 engaging the binder or the binder spring. At its lower end the shaft 27 is bent to provide an arm 29 shown as being in position for engagement by a cam 30, whereby the shaft 27 will be moved approximately vertically 10 endwise or axially when the arm 29 strikes the cam 30.

The cam 30 is here shown as being carried by a rod 31 slidable in a bracket 32 on the loom frame, whereby the arm can be adjusted by loosening its bolt 33 so as to position the cam properly. The bracket is pivoted at 32' and the height of cam 30 may be varied by changing the position of a bolt 33' in an arcuate slot 34' in the loom frame.

A spring 34 is connected at one end to the bearing 35 in which shaft 27 is journalled and is connected at the other end to a projecting pin 38 on the shaft 27, said spring being so positioned as to hold the arm 29 normally in position to be lifted by the cam 30, upon the forward movement of the lay.

A third arm 40 on the shaft 27 is positioned underneath the tail 24 of the dagger 23 and it will be seen that when the shaft 27 is moved axially, this arm 40 will swing the dagger about its pivot 41 into position to engage the frog 11 so as to cause the loom to be knocked off. Such action is, however, prevented when the shuttle is properly boxed, due to the fact that the shuttle acts through intermediate connections, including the arm 28, to oscillate the shaft 27 so as to place its arm 29 out of the way of the cam 30.

At the right hand end of the lay, or adjacent thereto, there is another shaft 42, which is mounted for oscillation in a bearing 43. This shaft has a rock arm 44 engaging the shuttle binder at the right hand end of the lay in the drawing (or its spring 20). Another arm 46 on shaft 42 is connected by a link 47 to an arm 48 on shaft 27 and through this connection it will 50 55

be seen that a properly boxed shuttle at the right hand side of the loom will act through the shaft 42 and link 47 to rock the shaft 27 to place its arm 29 out of the path of cam 30.

5. The operation of our device may be briefly restated as follows:

During the normal operation of the loom when the shuttle enters the box adjacent the magazine side (at the left hand side of Fig. 1) it will 10 act through the binder, binder spring and arm 28 to rock shaft 27 and move its arm 29 to a position where it will not strike the cam 30 as the lay beats up. Similarly, when the shuttle is properly boxed at the right hand or shipper handle side of the loom it acts through the binder and binder spring and rock arm 44 to oscillate the shaft 42, which through rock arm 46, link 47 and rock arm 48, swings the shaft 27 against the tension of its spring 34 into inoperative position with 15 reference to cam 30. Should the shuttle not be properly boxed at either end of its path, the parts above referred to will not be moved, whereupon the arm 29 will ride up on cam 30, moving the shaft 27 axially upward and causing arm 40 to 20 lift the tail of the dagger, swinging it against the tension of springs 25 which normally hold it in idle position, into the operative position, where it engages frog 11 and stops the loom.

The invention is here illustrated in connection 30 with a loom of the Northrop type, but it will be obvious that its application is not limited to looms of that type, and it will also be obvious that many changes may be made by those skilled in the art from the device as herein shown and described, all without departing from the spirit of the invention; therefore, we do not limit ourselves, except as indicated in the appended claims. While it is shown as a purely mechanical device it might obviously be operated electrically or otherwise.

40 We claim:

1. In a loom having a lay, a shuttle binder thereon, a shuttle and means for stopping the loom, the combination of a dagger, means for holding the dagger stationary in idle position during the normal operation of the loom, and means controlled by the binder for moving the dagger into operative position for stopping the loom when the shuttle is not properly boxed, said means including a fixed cam on the loom frame, 45 means normally positioned to be engaged by said cam and to be actuated thereby for moving the dagger into operative position as the lay beats up, and means operated by a properly boxed shuttle to disable said dagger-moving means.

55 2. In a loom having a lay, a shuttle binder thereon, a shuttle and means for stopping the loom, the combination of a pivoted dagger, means for holding the dagger stationary in idle position during the normal operation of the loom, and means controlled by the binder for moving the dagger into operative position for stopping the loom when the shuttle is not properly boxed, said means comprising an arm carried by the lay, 60 means for lifting said arm to swing the dagger into operative position, and means controlled by the binder for disabling said lifting means whenever the shuttle is properly boxed.

65 3. In a loom having a lay, a shuttle binder

thereon, a shuttle and means for stopping the loom, the combination of a dagger, means for holding the dagger stationary in idle position during the normal operation of the loom, and means controlled by the binder for moving the dagger into operative position for stopping the loom when the shuttle is not properly boxed, said means comprising a shaft mounted to oscillate and to move axially, connections from said shaft to the dagger, means for moving the shaft endwise to move the dagger into operative position through said connections, and means controlled by a properly boxed shuttle for disabling said shaft-moving means.

4. In a loom having a lay, a shuttle binder thereon, a shuttle and means for stopping the loom, the combination of a dagger, means for holding the dagger stationary in idle position during the normal operation of the loom, and means controlled by the binder for moving the dagger into operative position for stopping the loom when the shuttle is not properly boxed, said means comprising a shaft mounted for oscillatory and axial movement, an arm on the shaft below the adjacent end of the dagger, a cam fixed 25 on the frame of the loom, an arm on the shaft for engaging said cam to move the shaft axially and so bring the dagger into operative position when the shuttle is not properly boxed, and means actuated by a properly boxed shuttle for 30 oscillating said shaft to move the second-named arm out of position for engaging said cam.

5. A device as in claim 3, including resilient means for holding said second arm in position to engage said cam.

35 6. In a loom attachment, a protector rod, a dagger thereon, resilient means for holding the dagger in idle position, means mounted on the lay but independently of the dagger for moving the dagger toward active position upon the beat-up of the lay, a shuttle feeler, and means actuated through said shuttle feeler by a properly boxed shuttle for disabling said dagger moving means.

40 7. In a loom attachment, a protector rod, a dagger thereon, means for normally holding the dagger stationary in idle position during operation of a loom to which it is attached, a vertically movable member, means including a cam adapted to be fixed to a loom frame for actuating said vertically movable member to move the dagger into operative position, a shuttle feeler, and connections from said shuttle feeler to said vertically movable member for preventing operation thereof if the shuttle is properly boxed.

45 8. A device as in claim 7, including a fixed bearing on the lay for said vertically movable member.

55 9. In a loom stop motion, a protector rod, a dagger thereon, a frog adapted to be engaged by the dagger for stopping the loom, means mounted on the lay independently of the dagger adapted to act on the dagger at the rear end of the dagger for moving it into operative position as the lay beats up, a shuttle feeler, and means actuated through said shuttle feeler by a properly boxed shuttle for preventing operation of said dagger-moving means.
